UNITED STATES PATENT OFFICE.

ELBRIDGE G. WEST, OF CANANDAIGUA, NEW YORK.

STOVE-PIPE THIMBLE.

SPECIFICATION forming part of Letters Patent No. 247,450, dated September 20, 1881.

Application filed July 27, 1881. (Model.)

To all whom it may concern:

Be it known that I, ELBRIDGE G. WEST, of Canandaigua, in the county of Ontario and State of New York, have invented certain new 5 and useful Improvements in Stove-Pipe Thimbles; and I do hereby declare that the following is a full, clear, and exact description of the invention, which will enable others skilled in the art to which it appertains to make and use 10 the same, reference being had to the accompanying drawings, which form a part of this specification.

This invention relates to stove-pipe thimbles, and has for its object to combine simplicity in construction, saving of material, and effectiveness against fire or other dangers and inconveniences apt to arise when the stove-pipe comes in direct contact with the wood or metallic casing; and to that end it consists in 20 certain improvements in the construction and arrangement of parts, substantially as will be hereinafter more fully described, and particularly pointed out in the claim.

In the annexed drawings, Figure 1 represents a plan view; Fig. 2, a vertical sectional view; and Fig. 3, a horizontal sectional view on the line *x x*, Fig. 2.

Corresponding parts in the figures are denoted by the same letters of reference.

Referring by letter to the accompanying drawings, A designates a double cylindrical casing, constructed of tin, malleable or wrought iron, or any suitable material, and composed of the outer circular wall, B, and inner circular 35 wall, C, leaving an air-chamber, D, between said walls, which are connected by circular top and bottom plates, E F, respectively. These circular plates are provided with perforations G, to allow free circulation of air through the 40 air-chamber between the outer and inner walls of the casing A, and have their inner edges beveled inward, as shown at H, over which beveled ends the edges I of the inner wall are turned or bent, thus effecting a saving in material.

J J are fluted rings, (which rings may as well be corrugated or beaded,) depending by means of hangers or brackets *a* from the plates E F inside the inner wall, C, of the casing, and 50 serving to keep the latter in position, against which rings the stove-pipe K rests when it is inserted through the thimble, thus also leaving an air space or passage between the stove-pipe and inner casing, and keeping the former 55 from direct contact with the latter.

By reference to the foregoing description, taken in connection with the accompanying drawings, the advantages and uses of my invention will be readily understood.

In cases where it is desired to pass a stove-pipe through the ceiling of a room to the floor above my invention will be found especially useful. Heretofore in such cases, owing to defects in the arrangement and construction of the thimbles, the wood-work has frequently 60 caught fire from the heat imparted by the stove-pipe to the casing and from thence to the wood; but my invention obviates all liability of such accidents, there being two air-passages between the stove-pipe and wood—one between the 65 stove pipe and inner wall of the casing, formed by the interposed fluted, corrugated, or beaded ring, and the other between the inner and outer walls of the casing, by means of the perforations in the top and bottom thereof. 75

The depending ring may be dispensed with altogether at one end of the thimble, as may also the circular bottom plate of the casing, without materially affecting the nature of my invention. And my improved thimble will be 80 found to be very effective in its objects, and at the same time inexpensive, durable, and simple.

I am aware that a fluted ring is old in combination with a stove-pipe thimble, as shown 85 in the patent to Woodruff, No. 106,528. I am also aware of the patents to Brooks, No. 38,727; Pierce and Smith, No. 109,838; Harris, No. 71,300, and Buttles, No. 131,846; and I claim nothing therein shown; but, 90

Having thus described my invention, what I claim as new, and desire to secure by Letters Patent of the United States, is—

As an improvement in stove-pipe thimbles, the combination, with the herein-described 95 double drum or casing, of a fluted ring suspended detachably between the said double drum and the stove-pipe, substantially as herein described, for the purpose shown and specified.

In testimony that I claim the foregoing as my own I have hereto affixed my signature in presence of three witnesses.

ELBRIDGE G. WEST.
